CLAIM

The ornamental design for a recessed fan with light as shown and described.

DESCRIPTION

FIG. 1 is a front, right, top axonometric view of a recessed fan with light showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

In the drawings, the broken lines show portions of a recessed fan with light that form no part of the claim.

1 Claim, 5 Drawing Sheets(56)
